Inventor,

Henry P. Berck
by O. A. Bishop.

Atty.

UNITED STATES PATENT OFFICE.

HENRY P. BERCK, OF CHICAGO, ILLINOIS:

TIPPING SHELF FOR THE PRESERVATION OF GARBAGE OR ASH CANS.

SPECIFICATION forming part of Letters Patent No. 695,425, dated March 11, 1902.

Application filed June 19, 1901. Serial No. 65,218. (No model.)

To all whom it may concern:

Be it known that I, HENRY P. BERCK, a citizen of the United States, residing at 1080 West Harrison street, Chicago, in the county of Cook, State of Illinois, have invented new and useful Improvements in Tipping Shelves for the Preservation of Garbage or Ash Cans, of which the following is a specification.

My invention relates to improvements in receptacles for garbage, in which a horizontal shelf fixed to a vertical back with suitable braces or stays extending to the shelf, is arranged to tip outwardly on pivots connecting it with a fence or wall.

15 In many cities the law specifies metal garbage-cans of different sizes and does not permit the use of fixed boxes or barrels in the streets or alleys, and the scavenger will not enter the yards to remove their contents. Hence it is necessary to leave them sitting in the street or alley, where they are often broken by wagons as they pass through, and frequently they are stolen by junkmen and sold as second-hand cans.

20 Therefore the object of my invention is to provide a safe and convenient method for withdrawing the cans from the yard and returning when their contents are emptied. I attain this object by a mechanism illustrated 25 in the accompanying drawings, in which—

Figure 1 is a front elevation of yard side of the shelf with cans sitting on the shelf, showing all parts of the device. Fig. 2 is a side elevation, with a portion of the stay or side cut away, showing cans resting on the shelf in a vertical position. The broken lines show the position of the device when tipped outward into the alley ready for the withdrawal 30 of the cans. Fig. 3 is a vertical sectional view cut on line 22, Fig. 1.

Similar letters refer to similar parts throughout the several views.

In constructing my shelf I prefer to use wood. However, it may be made of metal or any suitable material. The back *b*, consisting of ordinary inch boards, is nailed or screwed to and along one edge of the shelf *e* at a right angle to the plane of the shelf. The top edge of the boards composing the back 45 is secured to a cleat *b'*. Side pieces *d* are fixed to the back and extend down to the shelf,

where they are fixed to it, forming a stay to support it. Cleats *f* are fixed to the outside of each end piece at an angle of sixty degrees and constitute a stop when the shelf is tipped outward, as shown in Fig. 2 by the broken lines. Strips *d'* of a suitable thickness are fixed in each lower corner; also, halfway up toward the top of the side pieces near the tops of the cans; also, one in the center on the shelf *e*. The side strips are designed to keep the cans from the sides. The one in the center is intended to keep the cans separated. The covers *i* are hinged to the inside of the sides *d* and are set at a suitable height in such way that when closed down they will rest level on top of the cans. An aperture is cut in the fence *a* or barn-wall, adapted to receive the back of the shelf. It is then placed in the aperture, and hinges or pivots *g* are fixed to the lower edge, connecting the shelf with the fence or wall. Two stakes *h* are driven in the ground at a suitable height for the shelf to rest upon when loaded and in a vertical position. A handle is provided on alley side to enable the scavenger to pull it out when he wishes to empty the cans.

In operation the scavenger pulls the shelf out at an angle, where it rests against the stops. Then withdrawing the cans after emptying them he replaces them on the shelf, pushing it back to a vertical position, where they rest secure within the yard or barn, as the case may be.

I am aware that tipping garbage-receptacles pivoted to a fence or wall are not new. Hence I do not claim a garbage-receptacle broadly; but

What I do claim, and wish to secure by Letters Patent, is—

In a tipping shelf, for the preservation of garbage-cans, having vertical back and side pieces supporting a shelf, the stop-cleats *f* fixed to each side, adapted to engage the fence or wall, the covers hinged to the inner sides arranged to fall inwardly on top of the cans, the fender-cleats *d'*, the stakes *h*, adapted to support the shelf as set forth.

HENRY P. BERCK.
